CLAIM

The ornamental design for a display screen with a graphical user interface, as shown and described.

DESCRIPTION

FIG. 1 is a front view of a display screen with a graphical user interface showing a first image in a sequence according to our new design; and,

FIG. 2 is a front view of a display screen with a graphical user interface showing a second image in the sequence according to our new design.

The dashed outer lines shown in FIGS. 1 and 2 illustrate the perimeters of the display screen and form no part of the claimed design. Also, the dashed text in FIGS. 1 and 2 forms no part of the claimed design.

The appearance of the transitional image sequentially transitions from the image of FIG. 1 to the image of FIG. 2. The process or period in which one image transitions to another image forms no part of the claimed design.

1 Claim, 2 Drawing Sheets
